(57) **CLAIM**

The ornamental design for a computer display screen with a graphical user interface, as shown and described herein.

DESCRIPTION

FIG. 1 illustrates a computer display screen with a graphical user interface according to a first embodiment; and, FIG. 2 illustrates a computer display screen with a graphical user interface according to a second embodiment. The outermost broken lines illustrate a computer display screen and form no part of the claimed design. The remaining broken lines illustrate portions of the graphical user interface that form no part of the claimed design.

1 Claim, 2 Drawing Sheets

FIG. 1

FIG. 2
